BASEBALL SCORING DEVICE

Frank Marshall and Roy M. Organ, Girard, Ill.

Application December 20, 1934, Serial No. 758,487

5 Claims. (Cl. 116—120)

This invention relates to a device which is designed and adapted to be used for scoring the performances of baseball players and the results of a baseball game as it is being played by opposing teams.

The principal object of the invention is the provision of a novel device of the indicated character which may be used by a person in the home or elsewhere as a baseball game is being broadcast over the radio.

The invention resides in the features as described in the following specification, defined in the appended claims, and illustrated in the accompanying drawings, in which:

15 Fig. 1 is a view of a board and various elements used in conjunction therewith constituting the device of the invention.

Fig. 2 is an enlarged section taken on the line 2—2 of Fig. 1.

20 Fig. 3 is a perspective view of one of the player-name plates.

Fig. 4 is a view of the pegs or pins used for respectively indicating the player at bat, the inning being played, and the strikes, balls, and outs.

25 Fig. 5 is a view of the pegs or pins used for respectively indicating the players on base of the opposing teams.

Fig. 6 is a view of the type of pegs or pins used for scoring totals.

30 Fig. 7 is a view of the type of pegs or pins used for indicating the players' positions.

Fig. 8 is a view of the type of pegs or pins used for scoring hits and the innings in which 35 they were made.

The device of the present invention, as illustrated by way of example in the accompanying drawings, includes a board 10 of any suitable material and of any suitable size and shape. The board 10 is made preferably of wood and is rectangular in shape. The top surface of the board 10 is sub-divided by rulings or lines into sections for two baseball teams, said sections being designated 11 to 19 inclusive, respectively. The sections 11 to 19 inclusive are arranged in vertical columns side by side. The sections 11 are designated by the name of the baseball teams which are the St. Louis Cards, and Detroit Tigers in the present instance. The name of each team is painted or inscribed on a suitable plate 20 removably arranged on pins projecting upwardly from the board 10. The columns of sections 12 to 19 inclusive are designated "Players pulled," "Hits," "Runs," "Home runs," "Inn.," "Errors," 50 "Strike outs," and "Base on balls," respectively.

These indices are designated 21, and are at the top of the columns. Spaced pins 22 project upwardly from the board 10 in each of the sections 11 to receive a plate 23, on which is printed or inscribed the name of one of the players, the 5 plate being provided with holes 24 in the underside thereof to receive the pins 22. The plate 23 is shown most clearly in Fig. 3, and the manner in which it is placed on the pins 22 is shown most clearly in Fig. 2. Adjacent each name plate 10 23 is a hole 25 in the board 10 within each section 11, to receive a headed peg or pin 26 having printed or inscribed thereon in abbreviated form the player's position on the team. This type of peg or pin 26 is shown most clearly in Fig. 7. 15 Any suitable number of these pegs or pins 26 may be used, and in the present instance there are thirty-eight. The board 10 has a suitable number of holes 27 therein to receive the pegs or pins 26 when not in use. Spaced pins 28 project upwardly from the board 10 within each of the sections 12 to receive the name plate 23 of the player "pulled" from the game during the progress thereof. There are two holes 29 in the board 10 within each of the sections 12 adjacent the pins 25 20 28 to receive one or two pegs or pins 30 to indicate the particular inning in which the particular player was "pulled" from or taken out of the game. In the present instance there are shown one hundred and thirty-seven pegs or pins 30 30 numbered in groups from one to twelve inclusive. These pegs or pins 30 are shown most clearly in Fig. 6, and the numbers thereon are designated 31. The board 10 has a suitable number of holes 32 therein to receive the pegs or pins 30 when 35 not in use. It is to be understood that any suitable number of these pegs or pins 30 may be used for the purpose of indicating the inning in which a player was "pulled" from or taken out of a game, hits, runs, home runs, errors, strike outs, 40 base on balls, and innings, provision being made for a twelve-inning game in the present instance although there is no limitation in this respect. Therefore it will be understood that the pegs or pins 30 are used for indicating the particular 45 inning in which a hit (single), run, home run, error, and strike out were made, and the inning in which a base on balls was received by a player. For instance, as shown in Fig. 1, the player Medwick made a single in the first and second innings, 50 a run in the first inning, and also received a base on balls in the first inning. Use is made of a plurality of distinctive pegs or pins 33, there being seventy-two of these in the present instance. The board 10 has a suitable number of holes 34 there- 55

in to receive the pegs or pins 33 when not in use. This type of peg or pin is shown most clearly in Fig. 8. These pegs or pins 33 are used for indicating two and three base hits, and the 5 innnings in which they were made, and to this end each peg or pin 33 has a top number 35 which indicates the particular inning, and a bottom number 36 which indicates the total bases. For 10 instance, as shown in Fig. 1, Goslin got a two-base hit in the first inning, White got a three-base hit in the second inning, and Owen got a two-base hit in the second inning. Each of the sections 13, 14, 15, 17, 18, and 19 has a suitable number of holes 37 to receive the pegs or pins 30 and 33 15 as the case may be. Each of the sections 13, 14, 17, 18, and 19 has six holes 37, and each section 15 has three holes in the present instance. Each of the sections 16 has one hole 37, and this hole is designated by the numbers 1 to 12 inclusive, 20 to indicate the innnings, the number being designated 38.

In accordance with another feature of the invention, the board 10 has printed or inscribed thereon lines 39 representing a baseball diamond, 25 and holes 40 in the board 10 represent the home plate and the three bases. Use is made of two groups of pegs or pins 41 and 42 respectively, there being four pegs or pins to each group, and the pegs or pins 41 are black, and the pegs or pins 42 are green to be distinguished from the former. The pegs or pins 41 are used to represent the base runners of one team, and the pegs or pins 42 are used to represent the base runners 30 of the other team. These pegs or pins 41 and 42 are used during the progress of the game. The black pegs or pins 41 represent the St. Louis players, and as shown in Fig. 1, the St. Louis team has players on first and second bases. The board 10 has holes 43 therein to receive the pegs or pins 40 41 and 42 when not in use.

In accordance with another feature of the invention, the board 10 has three holes 44 therein, designated by the numbers 1, 2, and 3, respectively, and the word "Strikes," for the obvious purpose of denoting the number of strikes on a particular batter. This indicia is designated 45. The board 10 also has four holes 46 therein which are designated by numbers 1, 2, 3, and 4, respectively, and the word "Balls" printed on the board, this 50 indicia being designated 47. The holes 46 are intended for the obvious purpose of indicating the number of called balls on the batter. The board 10 also has three holes 48 therein designated by the numbers 1, 2, and 3, respectively, 55 and the word "Outs," for the obvious purpose of indicating how many men have been put out during an innning. The indicia for the holes 48 is designated 49. Use is made of three pegs or pins 50 of a distinctive color in conjunction with the holes 44, 46, and 48 to keep a tally of the strikes, 60 balls, and outs. The board 10 has three holes 51 therein to receive the pins 50 when not in use.

Above each of the columns of sections 13, 14, 17, 18, and 19, there are two holes 52 in the board 10, and above the column of sections 15 there is one hole 52 in the board 10 to receive appropriate pegs or pins 30 to indicate the totals of the hits, runs, home runs, errors, strike outs, and base on balls. The word "Totals" is printed or inscribed on the board 10 above the holes 52, as at 53.

Use is made of a black peg or pin 54 and a red peg or pin 55 for each of the teams. The peg or pin 54 is used for indicating the particular player at bat. This is accomplished by removing the pin

26 beside the name plate of the player and inserting the peg or pin 54. As shown in Fig. 1, it is Martin's turn at bat. The red peg or pin 55 is received in one of the holes 37 to peg the particular innning being played.

Provision is also made for scoring the performances of "pinch hitters." To this end the board 10 is ruled to provide a suitable number of sections for the player-name plates representing the "pinch hitters," two such sections being shown in 10 the present instance under an appropriate heading 60, the sections being designated 61. Spaced pins 62 are in each section 61 similar to the pins 22, and spaced holes 63 in the board are also within each section 61 adjacent the pins 62, one 15 of which receives a peg or pin 26 to denote the player's position on the team and the other hole to receive a peg or pin 30 or 33 to denote the kind 20 of hit made and the innning in which it was made.

From the foregoing, taken in connection with the drawings, it will be obvious that the device may be used for scoring the performances of the players and for totaling the results of a baseball game as it is being played by opposing teams. The performances of the players scored are "offensive," and it is to be understood that if desired provision may be made for scoring the "defensive" performances or plays of the players, and that other variations may be made within the spirit of the invention as expressed in the appended claims.

We claim:

1. A scoring device comprising a board, a series of player-name plates, means on the board to removably retain said plates in a definite order 35 on the board, said board having groups of holes therein in alinement with each of said plates as retained on the board, each group of holes being appropriately designated by means on the board to denote various performances of a player, a 40 plurality of scorers each having suitable scoring indicia, said scorers being designed for disposition in certain of said holes to score the performance of each player during the progress of a game, means on the board to removably retain 45 player-name plates of pulled players, and additional means on the board to removably retain pinch-hitter player-name plates.

2. A scoring device comprising a board, a series of player-name plates, means on the board to 50 removably retain said plates in a definite order on the board, said board having groups of holes therein in alinement with each of said plates as retained on the board, each group of holes being appropriately designated by means on the board to 55 denote various performances of a player, a plurality of scorers each having suitable scoring indicia, said scorers being designed for disposition in certain of said holes to score the performance of each player during the progress of a game, and additional means on the board to removably retain player-name plates of "pulled" 60 players, said board having holes therein adjacent the plates of the "pulled" players, and certain of said scorers being designed for disposition in said last holes to score the performance of the "pulled" players.

3. A baseball game scoring device comprising a board, team-name plates, means on the board to removably retain the plates in place on the 70 board, a representation of a baseball-diamond on the board, there being holes in the board at the points respectively coinciding with the home-plate and the three bases, said board having a group of holes therein and suitable indicia for 75

scoring "strikes" on a batter, said board having a group of holes therein and suitable indicia for scoring "balls" on a batter, said board having a group of holes therein and suitable indicia for scoring "outs," and pegs for insertion in the holes representing the bases to indicate base runners, means adjacent the means for removably retaining said team-name plates for removably retaining player-name plates of pulled players, 10 and additional means below said team-name plates to removably retain pinch-hitter player-name plates.

4. In a baseball game scoring device, a board having one face thereof subdivided into vertical and horizontal sections, the board having a group of holes therein within each of said vertical sections, said board having a suitable index at the top of said vertical sections, a plurality of scorers each having an index number thereon which 20 together with the index of any one of said vertical sections denote a specific performance, a plurality of scorers each having a plurality of index numbers thereon which together with the index of any one of said vertical sections denote 25 a specific performance in a particular inning, said scorers being singly receivable in said holes, means for removably mounting a player-name

plate at one end of each of said horizontal sections, means in one of said vertical sections for removably retaining the player-name plate of a pulled player, and means below all of said horizontal sections for removably retaining the 5 player-name plate of a pinch-hitter.

5. In a baseball game scoring device, a board having one face thereof subdivided into vertical and horizontal sections, the board having a group of holes therein within each of said sections, 10 said board having an index "Hits" for said sections, a plurality of scorers each having a number thereon denoting a "single" also a particular "inning," and a plurality of scorers each having two numbers thereon one of which denotes 15 a particular "inning" and the other denotes a plural "base hit," said scorers being singly receivable in said holes, means at one end of each of said horizontal sections for removably retaining player-name plates, means in each of said 20 horizontal sections adjacent said means for removably retaining the player-name plates of pulled players, and means below all of said horizontal sections for removably retaining pinch-hitter player-name plates. 25

FRANK MARSHALL.
ROY M. ORGAN.
